RHEOSTAT

Joseph Youhouse, Fairfield, Conn., assignor to
 Casco Products Corporation, Bridgeport, Conn.,
 a corporation of Connecticut

Original application January 28, 1942, Serial No.
 428,454. Divided and this application January
 14, 1947, Serial No. 721,979

11 Claims. (Cl. 201—67)

1

This invention relates to electrical rheostats, especially rheostats for controlling heating pads and the like wherein a plurality of heat adjustments is desired. This application is a division of my application, Serial No. 428,454, filed January 28, 1942; now Patent No. 2,415,858, entitled "Switch device" and issued February 18, 1947.

Rheostat control devices have been provided in the past and are well known for controlling or setting an electric heating pad to provide for various degrees of heat. Generally these rheostats or control devices have had included in their structure a casing and a manually operable member located exteriorly of the casing for manipulation by a user to adjust the setting of the rheostat. The arrangement of the casing and manually operable member was such that the user had to employ two hands in order to adjust the rheostat to its setting with any degree of convenience and certainty.

An object of the present invention is to overcome this disadvantage in prior rheostat type controls by the provision of a structure including a casing and manually operable member which are so shaped and arranged that but a single hand is required to conveniently adjust the rheostat.

In accomplishing this there is provided, in the specific embodiment of the invention illustrated herein as exemplary thereof, an elongate casing having a shape which may be comfortably received and held in the palm of the hand, the said casing carrying an adjustment wheel which with its periphery is so arranged that it may be quickly and conveniently manipulated by the thumb of the hand which holds the casing or by one of the other fingers of said hand. The remainder of the periphery of the wheel is enclosed and therefore shielded so that it cannot be opposed in its movements by contact with other fingers or another portion of the hand, or with adjacent articles. Also, the periphery of the adjustment wheel is provided with an anti-slip configuration which further facilitates its being turned by a finger of the hand which holds the casing. By this organization the adjustment of the heating pad for example is considerably simplified and made more convenient, and this is an important consideration since very often a person who is using the pad finds it difficult to grasp the control rheostat with both hands.

Another object of the invention is to provide a compact control rheostat as above which is of simple construction, requiring a minimum number of parts for performing several circuit control operations in a simple and effective manner, and

2

which has parts readily produced for instance by stamping or molding operations and capable of assembly with maximum economy.

Still another object of the invention is to provide a control rheostat of the above type which is positive and reliable in its operation at all times.

A feature of the invention is the provision, in a control rheostat, of a resistance coil of especially simple and efficient construction capable of economical manufacture in mass production.

Other features and advantages will hereinafter appear.

In the accompanying drawings:

Fig. 1 is a plan view of a rheostat control made in accordance with the invention.

Fig. 2 is a view of the control but with the cover removed.

Fig. 3 is an axial section of the control taken on the line 3—3 of Fig. 1.

Fig. 4 is a detail of the manually operable wheel of the control.

Fig. 5 is a side view of the resistance element of the control.

Fig. 6 is an end view of the resistance element.

Fig. 7 is a heating pad wiring diagram including the rheostat control.

Fig. 8 is a perspective view of the contactor of the control device, and

Fig. 9 is a fragmentary view of the control showing a modified arrangement of the resistance element.

The rheostat control device of the present invention as shown includes a casing 20 which may be conveniently manufactured of molded plastic.

The casing 20 when assembled is of elongate shape having tapered ends and a substantially oblong central transverse cross-section. It is separable into two parts 20a and 20b along a substantially axial plane parallel to its broader lateral surface.

The two parts are held together by means of screws 21 adjacent opposite ends of the casing, and at each end the edges of the casing parts are recessed to provide apertures 22 and 23 (when the two halves are assembled) to receive conductors extending into the interior of the control device.

Approximately at the center of the two casing halves 20a and 20b, their opposite lateral edges are recessed to form a pair of longitudinal slots

when the casing is assembled, through which an adjustment disk 25 carried within the casing may extend. The casing portion 20b is also provided with a sight opening or aperture 26 for observing a visual indicator or dial 27a. The sight opening 26 preferably has a central arrow tip 26a

at one side thereof for cooperation with the dial 27a to provide a reference point therefor.

A pair of conductors 28 entering the casing 20 through the aperture 22 thereof is adapted to connect the control device with a source of electric power. The ends of these conductors extend through grooves 29 in the interior of the casing on opposite sides thereof and are connected to a pair of terminal screws 30 and 31 carried by a web 32 formed in the casing half 20a. A web 33 is also formed in the central wall of the casing half 20a and comprises a semi-circular portion 33a adjacent the web 32 and oblong portion 33b extending toward the opposite end of the casing. The breadth of the oblong portions of the web 33 is such as to allow for a pair of clearance grooves 34 and 35 which extend between the said portions and the lateral casing walls to receive connectors by-passing the said web.

A central recess 36 substantially at the center of the casing half 20a is formed in the web 33 with an annular bearing surface 37 surrounding a central spindle-receiving cavity or bearing 38 at its base. The opposite half 20b of the casing is provided with a similar bearing cavity 39 disposed directly opposite cavity 38, said cavities receiving the ends of a spindle 40 serving as the shaft for the indicator dial 27a and the adjustment disk 25. The translucent dial 27a is attached to a collar 41 on the upper end of the spindle 40 adjacent the bearing 39, and a portion of its surface extends under the sight opening 26 which is offset from the axis of the spindle.

The adjustment disk 25 may be formed for instance of molded plastic material and is of generally circular shape. It comprises a hub 42 molded on spindle 40 on the opposite side of the disk collar 41, its lower surface forming an abutment to engage the bearing surface 37. The peripheral edges of the disk 25 extend through the lateral slots 24, so that the protruding arcuate portions of the said disk are available for its manipulation. By virtue of this arrangement, the casing 20 may be held conveniently in one hand, and the disk 25 rotated at will by a thumb or finger of the same hand. The peripheral edge of the disk 25 is knurled as indicated at 43 and is provided at intervals with buttons 44 arranged in predetermined relationship so as to provide means for adjusting the position of the disk by tactful sensation alone.

The portion 33b of web 33 has a transverse slot 45 therein, adjacent the circular recess 36, for receiving connector or resistor means, and beyond the slot two screws 46 and 48 are threaded into the web. An elevated portion of the web 33 beyond slot 45 forms an additional web 49, which carries a pair of terminal screws 50 and 51 adjacent end aperture 23. As indicated in Fig. 2, the three conductors 52a, 52b and 52c are connected to terminal screws 50, 51 and 48 respectively. These conductors are adapted to connect the control device to a device such as a heating pad to be controlled.

Terminal 30 is connected directly to terminal 51 by means of an insulated conductor 53 which lies in lateral groove 35 of the casing part 20a. Terminal 31 carries a resilient conductor strip or spring contact 54 which extends through lateral groove 34 of casing part 20a to a point opposite the spindle 40 or its bearing 38. An angular tip 55 on the spring contact 54 extends inward into the circular recess 36 through a radial groove or slot 56 in the side of the web 33, terminat-

inating just short of the hub 42. The spring contact 54 is mounted so that its resilience normally urges its tip 55 toward the top of the slot 56 in web 33.

5 A metal contactor 57, Fig. 3, comprises a circular cup-shaped portion 57a having a central aperture in its base adapted to receive the hub 42 of spindle 40, and comprises a pair of diametrically opposite radial wings 57b, each having a pair of folded lateral flanges or arms 57c. The exposed surface of each of the wings 57b is cylindrically convex. The arms 57c are adapted to engage the edges of a pair of correspondingly disposed apertures 58 in the adjusting disk 25 so that the disk 25 and contactor 57, when assembled as illustrated in Figs. 3 and 4, are coupled for mutual rotation.

20 A coiled compression spring 59 surrounds hub 42 and is supported at one end against the face of the disk 25. The opposite end of the spring 59 bears upon the base of the cup-shaped portion 57a of contactor 57. Thus, when the control device is assembled, spring 59 urges the contactor 57 toward the wall of the casing half 20a, and presses wings 57b toward the upper surface of web 33, Fig. 3, while the arms 57c thereof engage the apertures 58 in the disk 25 so that the contactor is rotatable thereby.

25 The tip 55 of resilient spring contact 54 is positioned beneath the lower surface of the cup-shaped portion 57a of the contactor and by virtue of its resilience, yieldably engages said contactor forming a continuous electric contact therewith in angular positions of the contactor.

30 The upper surface of web 33 is provided with a pair of integral raised portions 60 on opposite sides of the recess 36, having concave upper surfaces forming projections adapted to serve as insulating detents for yieldably holding the wings 40 57b of contactor 57 positioned transversely of the casing 20. One of these raised detents is split, as shown by the slot 56 through which the tip 55 of spring contact 54 extends.

35 The resistor element of the control device is in the form of a resistance coil 85 which comprises resistance wire wound around an insulating core 86, the element being press-fitted in the slot 45 of the casing half 20a.

40 The terminals 46 and 48 carry a pair of metal conductive clips or retainers 87 and 88 which extend toward the recess 36 and have narrowed contact surfaces as shown in Fig. 2 for engagement with the wings 57b of the contactor 57. The clips 87 and 88 overlie and are clamped against the 45 opposite ends of the resistance coil 85 and form electric contact therewith. The narrowed contact surfaces of the clips 87 and 88 are preferably flat so that they do not act as detents when engaging the wings 57b of the contactor 57.

45 A flat metal segment or sector contact 89 is provided to extend arcuately around the side of the recess 36 opposite the slot 45, the said contactor being anchored by a terminal screw 67 and overlying the arcuate portion of the web 33 and 50 terminating adjacent the raised insulating detents 60 of said web.

55 The dial 27a has the words "Off," "Low," "Medium," and "High," each repeated once, as shown in Fig. 4 and also has a pair of graduated scales 70 extending over arcs which correspond with the energizing adjustment ranges, said scales having numerical indicia which increase from low to high. All of the indicia on the dial 27a are consecutively visible in the sight opening 26 when the 75 wheel 25 is turned.

Terminal screw 67 is connected by a conductor or bus bar 70 to terminal screw 50, and hence to conductor 52a.

A U-shaped bracket 71 secured to the web 33 by a screw 72 carries between its arms a miniature luminous gaseous discharge tube 73, filled with some suitable gas, such as neon, at reduced pressure. The arms of bracket 71 extend between disk 25 and the translucent dial 27a so that the lamp is below said dial and aligned with the sight opening 26. Accordingly, when the lamp is illuminated, the indicia of the dial 27a are clearly visible in the sight opening. By using a gaseous discharge tube which generates substantially no heat, the control device may be safely operated for a relatively long period of time without danger of fire or damage by overheating. Since such lamps are not subject, as are incandescent lamps, to burning out they will in general remain operative indefinitely.

One terminal of the lamp 73 is connected by a wire 90 to a clip 91 carried by the terminal screw 67 threaded into the web 33. The opposite lamp terminal is connected by a wire 75 to one end of a resistor 76 which adapts the lamp for use at the line voltage. The resistor 76 is carried in a pocket 77 in the wall of the casing half 20a. The opposite end of the resistor 76 is connected by a wire 78 to the input terminal 30.

As a result of this construction, contactor 57, when rotated by disk 25 out of its transverse, insulated detent-engaging position in the casing 28, forms a bridge between sector contact 89 and various points on the resistance coil 85, or its terminal clips 87 and 88, and is accordingly adapted to connect these elements with terminal 31 through the spring contact 54-55.

The wiring diagram of the control device of Figs. 1 through 6 and a heating pad to be controlled thereby is shown in Fig. 7. The heating pad here comprises a main heating coil 92 with a pair of safety devices 93, such as fuses or thermostats (preferably the latter) included in its circuit. One end of the main heating coil 92 is connected to terminal 51 by conductor 52b, and thence through conductor 53 to input terminal 30 and conductor 28. The opposite end of the coil 92 is connected in series with a normally closed bimetal switch 94. The latter is connected through a pair of parallel circuits to the other input terminal 31 and its associated conductor 28.

One of these circuits traverses conductor 52c to terminal 48 and its associated clip 88 at one end of the resistance coil 85, then through the turns of the latter coil included between clip 88 and contactor 57, and finally through the latter and spring contact 54-55 to input terminal 31.

The other parallel circuit from the bimetal switch 94 to terminal 31 includes an auxiliary heating coil 95 in the heating pad, which is connected by conductor 52a to terminal 50. From the latter, it traverses bus bar 70, sector contact 89 and contactor 57, rejoining the first-described circuit at spring contact 54-55, carried by input terminal 31.

The auxiliary heating coil 95 is adapted, either alone, or in conjunction with the main heating coil 92 to control the temperature, and hence the operation, of the bimetallic switch 94. When the temperature of the bimetallic switch 94 is sufficiently raised by the heat generated in coil 95, possibly supplemented by that generated in coil 92, switch 94 opens, interrupting the circuit through coil 92 as well as the aforesaid parallel circuits. On cooling sufficiently, the bimetallic

switch automatically recloses and reestablishes the circuits.

It will be observed that contactor 57 upon clockwise rotation from the position in which it engages insulated detent 60 initially engages clip 87 at one end of the resistor coil 85, and simultaneously, sector contact 89. Referring to the wiring diagram of Fig. 7, it will be seen that the maximum number of turns of resistance coil 85 is thereby included in parallel with auxiliary coil 95. Upon continued clockwise movement, contactor 57, while remaining in engagement with sector contact 89, moves across the coil 85 including progressively fewer and fewer turns of the resistance 85 in parallel with the auxiliary heating coil 95. Finally, it reaches clip 88 at the opposite end of said resistance coil. At this point, the resistance 85 no longer remains in the circuit, while auxiliary coil 95 is shunted, and the full line voltage is impressed across the terminals of the heating coil 92.

Since the auxiliary heating coil 95 is connected in parallel with that portion of the resistance 85 which is included between contactor 57 and clip 88, the current flowing through the main heating coil 92 is equal to the sum of the currents in auxiliary heating coil 95 and resistance 85.

In order to avoid undue generation of heat in the control device, the resistance of auxiliary coil 95 is made very much smaller than that of the main heating coil 92, so that the maximum power converted into heat in resistance 85 is never more than a very small proportion of the total power supplied to the heating pad.

When the entire resistance coil 85 is included in the circuit, that is, when contactor 57 engages clip 87, auxiliary heating coil 95 carries the maximum proportion of the current flowing through the main heating coil 92, and accordingly, heats the bimetallic switch 94 with maximum rapidity causing it to open in the shortest possible time interval after closure of the circuit. As the resistance of that portion of resistor 85 included in the circuit is decreased by clockwise rotation of contactor 57, coil 85 carries more and more of the current, and auxiliary heater 95 less and less, so that the interval between each closure of the circuit and the succeeding interruption thereof by the bimetal switch 94 becomes correspondingly longer. Finally, when coil 85 is cut out of the circuit entirely by movement of contactor 57 into engagement with clip 88 at its opposite end, coil 95 carries substantially no current, and the closed-circuit interval of switch 94 becomes maximum. In fact, with this adjustment, the switch 94 is responsive only to the heat generated by coil 92, or if the latter is not arranged to operate the bimetal switch, it remains closed, leaving the control of the circuit to the auxiliary devices 93 which in this case are thermostats.

Since the rate of cooling of the switch 94, which determines the time interval required for its reclosing the circuits is substantially the same under any given condition of use, being a function of radiation and conduction of heat by the surrounding media, the longer the circuit-closing period of switch 94 becomes as a result of the aforesaid adjustment of contact 57, the greater is the cumulative or average electrical energy converted by heater coil 92 in a unit period of time, and the greater becomes the amount of heat generated in the pad.

Thus, upon moving the contact 57 clockwise by corresponding rotation of disk 25, through the arc defined by its engagement with coil 85, the

average power supplied to the pad may be progressively increased from a predetermined minimum to a maximum value. Clockwise rotation of the disk 25 beyond the point where contactor 57 engages clip 88, returns the contactor to its traverse position in which it engages insulated detents 60, and interrupts the circuit, not only to the resistance coil 85 and its associated circuits, but also to the sector contact 89.

As indicated in Fig. 7, lamp 73 is connected in series with its resistor 76, between terminal 30 and sector contact 89. Accordingly, in this case, the lamp is energized to illuminate dial 27a in sight opening 26 only while switch contactor 57 is turned to an energizing or circuit-closing position. However, energization of the lamp remains independent of the thermostatic switches 94 or 93 controlling the heating pad circuit. Lamp 73 could be connected to the terminals 30 and 31 if it is desired to illuminate the dial 27a while the control device is turned "off."

As shown in Fig. 4, the indicia on the dial 27a, and the buttons 44 on disk 25 are so arranged with reference to disk aperture 58, that when contactor 57 is positioned transversely of the casing 20 so that the heating coils in the pad are deenergized, the word "Off" on dial 27a appears below the sight opening 26, and only the knurled periphery 43 of disk 25 without any of the buttons 44, extends through the slots 24 in the side walls of the casing 20.

When the disk 25 is rotated clockwise so as to energize the resistor 85 the word "Low" on dial 27a appears in the sight opening 26, while arcuate portions of disk 25, each bearing a single button 44 at their approximate midpoint protrude through slots 24.

Further clockwise rotation of disk 25 to cut out one-half of the resistor 85 brings a pair of buttons 44 to the center of each of the protruding arcuate portions of the disk 25, and the letters "Med" (standing for "medium") on dial 27a appear below the sight opening 26.

Further clockwise rotation of the disk 25 aligns the word "High" with the sight opening 26, while each protruding portion of the disk 25 now carries three buttons 44. Meanwhile, contactor 57 engages clip 88 and cuts out the resistor 85 entirely.

The next clockwise manipulation of the disk 25 again positions contactor 57 transversely of the casing corresponding to the circuit-interrupting, starting position and the word "Off" again appears in the sight opening 26, the indicia on the dial 27a being repeated on each half thereof.

Thus, as a result of provision of the illuminated dial, and of the buttons 44 on the periphery of the disk 25, the control device can be adjusted to any desired setting in the dark by tactful sensation alone, or by visual observation of the dial in the sight opening.

The portion of the numerical scale on the dial 27a which is visible at the center of sight opening 26 gives an empirical indication of the power setting, while the accompanying words "Low," "Med" and "High" which are similarly visible, characterize the general state of adjustment. When the lamp is extinguished the control device is "off." The buttons 44 provide a tactful means for determining the setting of the control device.

In a modification of the control device of Figs. 1 to 6, shown in Fig. 9, clips 87 and 88 may be replaced by clips 61a and 62a, which are similar in shape to clips 61 and 62 and a clip 63a carried by a terminal screw 47a, may be employed in

conjunction with the resistance coil 85 of Figs. 1 to 6. Clips 61a and 62a, like clips 87 and 88 engage opposite ends of the resistance coil 85, while clip 63a engages the approximate midpoint of the said coil. The contact surfaces of the three clips are concave, so as to form detents cooperating with the movable contactor 57.

Operation of this modification is similar to that of the device of Figs. 1 to 6 except that the portion of the resistance coil 85 included in the circuit is not universally variable. Only three closed-circuit adjustments are possible, namely, "low," "medium" or "high," corresponding to inclusion of all, half or none of the turns of coil 85 in the circuit by engagement of contactor 57 with clip 61a, 63a or 62a respectively.

The construction of the resistance coil 85 as shown in Figs. 5 and 6 lends itself to convenient and economical manufacture by mass production methods. Instead of employing a unitary core, the core 86 consists of two separate rectangular halves. Resistance wire 96, having an insulating coating, is wound around the juxtaposed halves of the core 86, inserting the opposite ends 97 of the said ends of the coil. By this means, unwinding of the wire is effectively prevented and no special fastening means is required therefor.

To complete the coil, the insulation is removed from the outer surface of the wire 96 on that face of the coil 85 which is to be exposed at the top of the slot 45 so that the turns of the coil are adapted to form electrical contact with contactor 57, and with clips 87 and 88, or 61a, 62a and 63a.

Variations and modifications may be made within the scope of this invention and portions of the improvements may be used without others.

I claim:

1. In a rheostat, a resistance coil comprising a core of insulating material, said core having two separable portions; and a coil of resistance wire wound about said core, an end portion of said wire being held between the two portions of the core.
2. In a rheostat, a resistance coil comprising an elongate core having a substantially rectangular cross-section, said core being formed of insulating material and consisting of two elongate, laterally separable portions of rectangular cross-section; and a coil of resistance wire wound about said core, the ends of said wire being held between the two portions of the core adjacent the ends thereof.
3. A rheostat comprising a body of insulating material; a manually operable member rotatable on the body and having a pair of contact arms extending from it in opposite directions and yieldable thereon, said body having pairs of integral, spaced projections on opposite sides of the rotatable member, said projections being traversable by the contact arms and providing detents for said arms; a metal contact segment extending along one side of the rotatable member and between the pairs of projections of the body, said segment being engageable by one or the other of the contact arms; an elongate generally straight resistance element extending along the other side of the rotatable member between the pairs of projections of the body, said element being engageable by one or the other of the contact arms; and a pair of metal retainer fingers for the resistance element, located respectively adjacent corresponding projections of the said pairs, said retainer fingers overlying and contact-

ing the ends of the resistor element and being engageable by said contact arms.

4. A rheostat comprising a body of insulating material; a manually operable member rotatable on the body and having a pair of contact arms extending from it in opposite directions and yieldable thereon, said body having pairs of integral, spaced projections on opposite sides of the rotatable member, said projections being traversable by the contact arms and providing detents for said arms; a metal contact segment extending along one side of the rotatable member and between the pairs of projections of the body, said segment being engageable by one or the other of the contact arms; an elongate generally straight resistance element extending along the other side of the rotatable member between the pairs of projections of the body, said element being engageable by one or the other of the contact arms; and a pair of metal retainer fingers for the resistance element, one end of each finger being located respectively adjacent corresponding projections of the said pairs, the other ends of the fingers being remote from the said projections and being anchored to the casing, and the fingers being engageable by the said contact arms and intermediate their ends overlying the ends of the resistor element.

5. A rheostat comprising a body of insulating material; a manually operable member rotatable in the body and having a pair of contact arms extending from it in opposite directions and yieldable thereon, said body having a portion adjacent said arms and completely surrounding said member, and having on said portion pairs of integral oppositely-disposed spaced projections traversable by the contact arms, said projections providing detents for said arms; a metal contact strip extending along said portion of the body at one side of the rotatable member and between the pairs of projections of the body, said strip being engageable by one or the other of the contact arms; a resistance element extending along said portion of the body at the other side of the rotatable member and between the pairs of projections of the body, said element being engageable by one or the other of the contact arms; and a pair of metal retainer fingers for the resistance element, located respectively adjacent corresponding projections of the said pairs, said fingers overlying the ends of the resistor element and being engageable by the said contact arms and at least one of said fingers contacting said element.

6. A rheostat comprising a body of insulating material, a manually operable member rotatable in the body and having a pair of rigidly joined contact arms extending from it in opposite directions and yieldable thereon, said body having a circular portion adjacent said arms and completely surrounding said member, and having on said portion pairs of integral oppositely disposed spaced projections traversable by the contact arms, said projections providing detents for said arms; a metal contact strip extending along said portion of the body at one side of the rotatable member and between the pairs of projections of the body, said strip being engageable by one or the other of the contact arms; an elongate generally straight resistance element extending along a tangent to said portion of the body at the other side of the rotatable member and between the pairs of projections of the body, said element being engageable by one or the other of the contact arms; and a pair of metal re-

tainer fingers for the resistance element, located respectively adjacent corresponding projections of the said pairs, said fingers overlying and contacting the ends of the resistor element and extending laterally therefrom in a direction toward the rotatable member so as to be engageable by the said contact arms.

7. A rheostat comprising a body of insulating material; a manually operable member rotatable on the body and having a pair of contact arms extending from it in opposite directions and yieldable thereon, said body having pairs of integral spaced projections on opposite sides of the rotatable member, said projections being traversable by the contact arms and providing detents for said arms; a metal contact segment extending between the pairs of projections of the body, said segment being engageable by one or the other of the contact arms; a resistance element extending along the other side of the rotatable member between the pairs of projections of the body, said element being engageable by one or the other of the contact arms; and three metal retainer fingers for the resistance element, two of said fingers being located respectively adjacent corresponding projections of the said pairs and the third finger being located between said two fingers, all of said fingers overlying the resistor element and being engageable by the said contact arms, and at least two of said fingers contacting said element at different locations thereon.

8. A rheostat for controlling an electric appliance, comprising a hollow casing shaped to receive electrical conductors for connection to a source of current and to the appliance to be controlled, said casing being separable into two parts the edges of which are cut away to form a slot in a side wall of the casing; variable resistor means mounted within the casing; and a wheel within the casing connected with said resistor means to vary the same, said wheel having a peripheral portion protruding through the slot in the casing wall for manual engagement.

9. A rheostat for controlling an electric appliance, comprising a hollow casing shaped to receive electrical conductors for connection to a source of current and to the appliance to be controlled, said casing having a pair of oppositely located slots in opposite walls thereof; variable resistor means mounted within the casing; and a wheel within the casing connected with said resistor means to vary the same, said wheel having peripheral portions protruding through the slots in the casing wall for manual engagement.

10. A rheostat for controlling an electric appliance, comprising a hollow casing shaped to receive electrical conductors for connection to a source of current and to the appliance to be controlled, said casing being separable into two parts the edges of which are cut away to form a slot in a side wall of the casing; variable resistor means mounted within the casing; aligned bearing means formed in the respective casing parts; and a wheel within the casing, carried by said bearing means and connected with said resistor means to vary the same, said wheel having a peripheral portion protruding through the slot in the casing wall for manual engagement.

11. A rheostat for controlling an electric appliance, comprising a hollow casing shaped to receive electrical conductors for connection to a source of current and to the appliance to be controlled, said casing having a slot in its wall and having a sight aperture; variable resistor means

mounted within the casing; a wheel within the casing, connected with said resistor means to vary the same, said wheel having a peripheral portion protruding through the slot in the casing wall for manual engagement; and indicator means in the casing, movable with said wheel and disposed adjacent the sight opening to be visible therethrough.
